UNITED STATES PATENT OFFICE.

JOHN C. PINTER, OF CHICAGO, ILLINOIS.

PACKAGING MACHINE.

Application filed March 27, 1926. Serial No. 97,885.

My present invention relates to improvements in packaging machines adapted especially for packing bakery goods into receptacles or cartons. While the machine or apparatus of my invention is well suited for packaging various bakery goods and other similar articles, for convenience of illustration and description I have shown the present exemplification of my invention as particularly adapted for packaging biscuits (generally known as "crackers") usually twenty in number in cartons.

In carrying out my invention, the open cartons with the usual wax-paper liner therein, are supplied to the machine in suitable manner and deposited upon an intermittently moving endless conveyer belt which is located adjacent to a similar endless and intermittently moving cracker carrier, and means are provided for feeding the crackers in a row, continuously, to the carrier. The conveyer and carrier are arranged in parallelism and move synchronously, and means are provided for dividing the continuous row of crackers into charges complementary to the empty cartons moving with the conveyer in juxtaposition to the carrier. A ram or injecting mechanism, operating transversely to the line of movement of the charges and cartons, is employed to transfer successive charges to complementary cartons, and means co-operating with the ram mechanism are utilized to spread and retain the wax-paper liner or wrapper of the carton during the ramming operation. After the charge has been pushed or injected into a waiting carton, the filled carton is automatically transferred to an intermittently moving discharging conveyer for the filled cartons which are thereby conveyed to a succeeding station for subsequent operations.

The invention consists in certain novel combinations and arrangements of parts and novel features of construction for accomplishing the above steps in the operation of the machine as will hereinafter be more fully pointed out and claimed.

In the accompanying drawings I have illustrated one complete example of the physical embodiment of my invention wherein the parts are combined and arranged according to one mode I have thus far devised for the practical application of the principles of my invention. It will be understood that various changes and alterations of the ex-

emplified form of the invention are contemplated and can be made within the scope of my appended claims without departing from the principles of my invention.

Figure 1 is a plan view of a machine embodying my invention.

Figure 2 is an enlarged side view of a portion of the feed chutes and carrier for the crackers.

Figure 3 is a detail view at line 3—3 of Figure 2 showing the cracker carrier in section and illustrating one end of the feed chutes co-operating therewith.

Figure 4 is an enlarged, vertical sectional view, transversely of the cracker carrier, showing a cracker on the carrier, the ram-head, and the mechanism actuated by the ram for spreading and retaining the wax-paper liner or wrapper together with the discharging table for the filled carton.

Figure 5 is a perspective view of the filled carton, as it is conveyed from the machine.

Figure 6 is a detail view in elevation, showing the pivoted discharge table, and means for spreading and retaining the wax-paper liner.

Figure 7 is a top plan detail view partly in section of part of the wax-paper liner spreading mechanism.

Figure 8 is a view in side elevation (with the cracker carrier in transverse section) showing the actuating and operating mechanism of the spreading devices.

Figure 9 is a perspective view showing the position of the empty cartons as they are fed to the ramming mechanism.

As herein illustrated, the rectangular crackers A (Fig. 4) are packaged, usually twenty in number in the carton C while it is in the position of Figure 9 wherein the top fold C' and insert fold C² form the bottom of the receptacle, and the wax-paper liner or wrapper W is spread out and its four walls retained in position to permit the entrance of the charge of twenty crackers, which charge is forced or pushed into the body of the carton C. After the carton is filled, it is deposited in upright position of Figure 5, and carried away for further treatment.

In order that the general assembly and arrangement of parts may with facility be understood, it will be seen in Figure 1 that I have indicated a motor 1 with its drive shaft 2 connected with a reduction gear in the gear casing 3, and the driven shaft 4 at

- the opposite side of the gear casing is equipped with a ratchet mechanism 5 for imparting an intermittent rotary movement to the operating shaft 6. The operating shaft 5 is provided with a drum 7 having suitable sprockets (not shown). The carton conveyer is an endless belt 8 of suitable length and of a width to support the cartons in the horizontal position of Figure 9 and, is provided 10 with sprocket chains that pass around the drive drum 7 and also around a complementary supporting drum 9. The cartons are approximately eight inches long and at regular intervals throughout the length of the 15 conveyer belt, spaced, transversely arranged push plates 11 are fixed thereon to form spaces or intervals in which the empty cartons are deposited, as by hand.
- The empty cartons are deposited, either 20 manually or automatically at the right end of the conveyer in Figure 1, with their open sides toward a cracker carrier 12, which is also an endless belt, located adjacent to and parallel with the carton conveyer, and 25 travels intermittently in the same direction as the carton conveyer, as indicated by the arrows in Figure 1. The conveyer belt 8 with its drums 7 and 9 on the respective shafts 6 and 10 terminates at both ends 30 short of the cracker carrier to accommodate an operator who will usually be stationed at the ends of this conveyer, for the purpose of maintaining proper movement of the crackers and cartons, if required.
- The cracker carrier is provided with one 35 or more sprocket chains 13 at the inner sides of its flights which pass over the drive sprockets of the drum 7, and at its ends the carrier passes around guide drums 14 and 15 40 supported to rotate with their shafts in suitable bearings.
- The carrier 12 is also provided with spaced, transversely extending push plates 16, each having a central finger or projecting 45 extension 17, and these push plates are alined with the series of push plates 11 on the carton conveyer as indicated in Figure 1.
- The crackers are fed in a continuous row 50 to the carrier at the right end of Figure 1, while standing on edge, by means of a pair of inclined, longitudinally disposed feed belts 18 and 19 located above the carrier, spaced at the sides of its longitudinal center, and suitably driven to pass around the 55 end rollers 20 provided therefor. As seen in Figure 2 the feed belts deliver the crackers in a continuous row, to a pair of declining chutes 21 and 22 disposed above the lateral edges of the carrier and at the outer ends 60 of the push plates 16, and a complementary declining, upper, or top guide plate 23 is used to guide the row and charges of crackers along the feed belts and chutes to the cracker carrier in order that they may be 65 carried along while standing erect, or on one edge. As the row of crackers pass from the feed belts 18 and 19, the crackers are divided into charges (say twenty crackers to a charge) by means of the fingers or extensions 17 of the push plates 16. The successive fingers pass between the longitudinally disposed belts 18 and 19 and their rollers and shafts, and as the row of crackers descends, two adjoining crackers are separated by an extension, thus forming successive, spaced, charges of twenty crackers to a charge.
- As the successive charges are carried to the left in Figure 1, they are successively pushed or injected into a complementary, 80 waiting carton C. The carton lies on the conveyer in the position of Figure 9 with the two end walls C³ of the carton (which are folded inwardly when the carton is being closed) in vertical position and projecting with the wax-paper liner W toward the carrier, in order that the charge of crackers may be pushed into the open side of the carton. The open carton is delivered by the conveyor 8 to a pivoted or drop table 24, having a side abutment 25 against which the carton is arranged for proper alinement. A ram head 26 reciprocates transversely of the carrier and above it to push the charge of crackers into the carton on its working stroke, and means are provided for spreading open and retaining the four walls of the wax-paper liner W to readily permit the entrance of the charge into the carton, or into the wrapper within the carton. 100
- The ram head 26, which is an upright, oblong shaped plate that may be slotted as indicated in Figure 6, is carried by an open frame or slide 27 having guide ribs that slide in grooves or guideways in the top surface of an open supporting frame 28, and lugs 29' or other suitable means may be employed to retain the slide in proper relation to its supporting, fixed plate or frame 28. The slide and its integral or rigid head 110 are reciprocated through the co-action of a rack bar or plate 29 carried at one edge of the slide, and an arcuate rack lever or segmental gear 30, a spring 31 being employed to facilitate the movement of the reciprocating slide.
- The segmental gear 30 is pivoted at 32 on a bracket 33 supported laterally from the frame 28, and a crank arm 33' is operated by a link 34 and eccentric 35 on the shaft 4 for converting the rotary movement of the shaft to reciprocating movement of the link and slide, the latter in a direction at right angles to the movement of the link. 120
- For spreading and retaining the walls of the wrapper W to permit entrance of the charge of crackers to the wrapper or carton, four pivoted plates 36, 37 and 38, 39 are arranged in pairs to swing into the opening of the wrapper, as in Figure 6, in advance 125

of the ram head, and then by a reverse movement to swing out of the open end of the wrapper after the ram has receded or been retracted by spring 31, the movement of the plates being indicated by arrows in Figures 4 and 7.

The two vertically disposed plates 36 and 37 spread the end walls of the wrapper, and the plates 38 and 39 spread the upper wall 10 and flatten the lower wall of the liner as it lies in the carton on the table.

The end plates 36 and 37 are fixed to turn with two vertically disposed shafts 40 and 41 which are journaled to revolve in bearings in the supporting frame B. The upper plate 38 is fixed to revolve or swing with the horizontal shaft 42 which is journaled in bearings in the frame B and provided with a coiled retracting spring 43 at one end 20 (Fig. 6) to assist in returning the plate to vertical position after withdrawal of the ram head. The lower plate 39 is fixed to revolve with a pair of trunnions or stud shafts 44 and 45 journaled in bearings in the frame B and the four plates are caused to swing through an arc of ninety degrees with the stud shaft 42 used as a drive shaft for the lower and upper plates. The operating shafts for the plates are caused to turn 25 on their axes at the initial movement of the ram head in advance of its working stroke and immediately following its idle stroke.

In Figure 8 it will be seen that a side frame including an upright bar 46 is attached by bracket 47 (Fig. 6) to the slide 27, and a horizontal cam arm 48, at its front end, is designed to turn up a cam 49 on the shaft 42 with the initial movement of the working stroke of the ram.

40 To actuate the upper and lower plates and cause them to swing to operative position in advance of the ram head shown in the drawings, the rotary movement of the shaft 42 is transmitted to the lower shaft 44 by the upward movement of an inclined, connecting, double rack bar 50 having rack teeth, at its opposite sides to engage segmental gears 51 and 52 on the respective shafts 44 and 42.

50 The two side plates 36 and 37 are swung through an arc of ninety degrees with their shafts 40 and 41 as indicated by arrows in Figure 7 through the instrumentality of segmental gears 53 and 54 on the respective shafts, and a double rack bar 55 with rack teeth on its opposite sides connects these gears, a spring 55' being attached to the bar and to a portion of the frame B to assist in the return swing of the plates. This horizontal rack bar is adapted to reciprocate in supporting heads of the frame B and is actuated on its working stroke by the co-operation of a roller 56 carried by the bar and a cam portion 57 of a horizontal cam bar 58

60 disposed at approximately right angles to

the rack bar. The cam bar 58 as shown in Figure 8 is rigid or integral with the lower cam bar 48, forming the reciprocable side frame that is carried or supported by the slide 27, said frame including the upright 70 bar 46 and bracket 47.

For guiding the cam bar 58 in its reciprocating movement I provide a pair of rollers 59 and 60, journaled in suitable bearings of the frame B, the former roller at the side 75 of the bar and the latter roller located above the bar. It will be apparent that these rollers guide and support the side frame and retain it in operative positions as required.

The cracker carrier passes over a bed plate 80 B' supported on the frame B and presents successive charges of crackers to be transferred from the carrier to the drop or tiltable table 24.

After the carton has been filled and the retaining plates 36, 37 and 38, 39 have swung out of the wrapper as described, the filled carton which is resting on the table 24 against the abutment plate 25 of the table and a fixed abutment plate 61 of a supporting frame 62, the table is dropped to discharge the filled carton to an endless delivery conveyer 63 which is supported to travel through the frame 62.

The table is pivoted in the frame B by means of a shaft 64 and ears or lugs 65, the latter fixed to the table at its underside. By means of spring 66 attached to the lever arm 67 of the shaft and anchored to a portion of the frame B, the table is returned to and normally held in horizontal position at the outer side of the cracker carrier.

The table is tilted, as indicated by dotted arrow in Fig. 4 by means of a tappet 68 rigid with the shaft 64 and a bell crank 105 tappet lever 69 pivoted at 70 on a reciprocating tappet rod 71. The rod is suspended from the slide 27 as at 72 in Figure 8 and reciprocates through stationary bearings 73 suspended from the frame B in line with the longitudinal axis of the slide.

A spring 74 permits the bell crank tappet lever to swing backward on the outward or idle stroke of the tappet rod 71, but upon the return or working stroke of the rod the 115 tappet lever 69 engages the tappet 68 causing the table to be tilted on its axis or shaft 64, whereupon the filled carton is deposited, as indicated in Figure 4 upon the waiting 120 filled-carton conveyor 63.

Various changes may be made in the construction and operation of the apparatus or machine in its adaptation for different uses. The apparatus may be adapted to various sizes of cartons to be filled or packed, by varying the sizes of the compartments or spaces of the cracker carrier and carton conveyer, as well as the size of the ram head, and adjusting the stroke of the ram 125 and its operating mechanism.

It will be understood that the feed-row of crackers is formed by an operator or operators who pick the biscuits or crackers off the baking pans as they come from the 5 baking room, and the filled cartons as they are discharged from the apparatus are conveyed to a suitable closing agency.

The cracker carrier and the carton conveyer may be made of suitable material, 10 and of course are flexible, and the cracker carrier is preferably provided with a cushion or soft surface for the standing crackers in order that they may not be chipped when placed on the carrier. The soft or cushion 15 surface, which may be canvas, also prevents the crackers from falling to horizontal position as they move along with the carrier.

By the utilization of the machine or apparatus of my invention the crackers are 20 packaged in a sanitary manner and with comparatively slight loss due to breakage as compared with the breakage occurring under present practices of packaging the crackers, and a material reduction is assured in the 25 cost of labor, as it will be apparent that the necessity for hand-operators or manual labor is reduced, the reduction in some instances being as great as fifty percent.

Having thus described my invention, what 30 I claim as new and desire to secure by Letters Patent is:—

1. The combination with a charge-carrying cracker-carrier and a complementary carton-conveyer, and means for simultaneously and intermittently moving said carrier and conveyer, and a transversely arranged drop table adapted to receive successive cartons, of means for bodily transferring a charge from the carrier to a complementary carton between intermittent movements of the carrier and conveyer.

2. The combination with a horizontal charge-carrying cracker carrier, a parallel carton conveyer, and a transversely movable drop table adapted to receive successive cartons, of means for transferring a charge of crackers from its carrier to a carton supported on said table.

3. The combination with an endless belt forming a cracker carrier, a complementary endless belt forming a carton conveyer, and

a transversely arranged drop table adapted to receive successive cartons, of a transversely operating ram mechanism, and means actuated by said mechanism for controlling 55 the movement of said table.

4. The combination with an endless belt forming a charge-carrying cracker carrier, a complementary endless belt forming a 60 carton carrier, and a transversely arranged drop table, of a transversely operating ram mechanism, actuating means adapted to intermittently move said carrier and conveyer, and means operated by the actuating means for operating said ram mechanism and drop 65 table.

5. The combination with a ram mechanism adapted to insert a plurality of articles into a wrapper and carton, of spreader and retaining devices adapted to engage the 70 walls of said wrapper in advance of the working stroke of the ram mechanism, means for operating the ram mechanism, and means co-acting therewith for operating the spreader and retaining devices. 75

6. The combination with a ram mechanism adapted to insert a charge of crackers into a carton and its wax-paper liner, of a pair of upper and lower pivoted spreader plates, a pair of opposed pivoted end plates, 80 a cam device for operating each pair of plates, means for actuating the ram mechanism, and separate means carried by the ram mechanism for co-action with said cam devices. 85

7. The combination with a ram mechanism adapted to insert a plurality of crackers into a carton and its wax-paper liner, of a pair of horizontal rock shafts and upper and lower spreader plates thereon, a pair of vertical rock shafts and opposed end plates thereon, means for actuating the ram mechanism, a cam on a horizontal shaft and a cam arm on the ram for coaction therewith and operative connections 90 between said shafts, rack wheels on the vertical shafts, a reciprocable rack bar connecting said wheels, and a cam arm on the ram for coaction with said rack bar. 95

In testimony whereof I have affixed my 100 signature.

JOHN C. PINTER.
